UNITED STATES PATENT OFFICE.

JAMES R. CLUXTON, OF XENIA, OHIO.

PILLOW.

SPECIFICATION forming part of Letters Patent No. 391,300, dated October 16, 1888.

Application filed June 16, 1888. Serial No. 277,308. (No model.)

To all whom it may concern:

Be it known that I, JAMES R. CLUXTON, of Xenia, in the county of Greene and State of Ohio, have invented certain new and useful 5 Improvements in Pillows; and I do hereby declare that the following is a full, clear, and exact description thereof, reference being had to the accompanying drawings, and to the letters of reference marked thereon, which form part 10 of this specification, in which—

Figure 1 is a side view of my improved spring pillow or cushion partly in section. Fig. 2 is a cross-sectional view of the same. Fig. 3 is a detail view of the springs.

15 This invention is an improvement in cushions and pillows, and its objects are to provide a light, ventilated, and comfortable spring-pillow; and to these ends the invention consists in the novel construction and arrangement of 20 parts hereinafter described, illustrated in the drawings, and concisely stated in the claims hereto appended.

25 Referring to the drawings by letters, A indicates the frame of the pillow, which is composed of a series of **M**-shaped springs, B, having a coil at each of their angles to increase their pliability. The springs B are placed on their side or legs *b b*, and alternate springs face in opposite directions, as shown. The 30 legs *b* are connected by wires or straps C C at opposite ends, and by intermediate wires or straps, *c c*, which wires C C extend the length of frame A and keep the springs in proper relative position. Springs B are also connected 35 at their central bends by wires or straps *c' c'*, as shown, for further bracing the frame. This frame A is very flexible and yielding; but the depression of one part of the frame will cause the tensioning or compression of all 40 of the springs to a greater or less degree, so that the frame will not readily become distorted, owing to undue wear on any one spring.

45 The frame A, constructed substantially as described, is made up the desired size for a pillow or cushion, and it is then inclosed by a cotton sack, D, upon which a padding of “excelsior” or hair, E, is placed and secured to shape the cushion. Padding E is then covered by cotton batting *e* or other suitable material, and finally over all is drawn a tick or 50 sack, F, which holds the wadding in place,

thus affording a smooth soft surface to the cushion, which, if desired, may have a finishing-cover of any desired material. The end of the frame is preferably not covered, to permit free circulation of air therein, which greatly increases the comfort of the cushion in 55 warm weather.

G G are eye-loops secured to the upper and lower edges of the tick F at the sides thereof; and *g* are cords secured to an eye, G, at one corner of the cushion and then passed alternately through the remaining eyes on the upper and lower edges to the opposite end of the cushion. By tightening or loosening this cord 60 65 the height or thickness of the cushion can be regulated. It is then ready for the ordinary pillow dress or case.

Having described my invention, I claim—

1. In a pillow, the combination of a spring-frame having an exterior upholstering or cover, with the series of eye-loops on the side edges of the cover, and the cords passed alternately through opposite loops on the same side of the 70 pillow, substantially as specified.

2. The combination of spring-frame A, composed of **M**-shaped spring-wires B and brace-wires C, connecting said springs, with the covering-tick D, loop-eyes G on the side edges thereof, and the cords *g*, passed alternately 75 80 through the opposite eyes at the same side of the pillow, substantially as specified.

3. In a pillow, the combination of the frame A, composed of the springs B B, each formed of a single wire bent into an **M** shape and having a coil at each of its bends, said springs being set in alternate directions, and the wires C C, connecting the springs at the side edges of the frame, and the wires *c c*, connecting said springs at top and bottom and at their central 85 90 side bends at intermediate points between wires C C, with the inclosing upholstering for said frame, all substantially as and for the purpose specified.

In testimony that I claim the foregoing as my 95 own I affix my signature in presence of two witnesses.

J. R. CLUXTON.

Witnesses:

GEO. W. CONNER,
M. J. HARTLEY.
